UNITED STATES PATENT OFFICE.

CAY BUHL, OF PATERSON, NEW JERSEY, ASSIGNOR TO THE JOHNSON VAN VLAANDEREN MACHINE COMPANY, OF PATERSON, NEW JERSEY, A CORPORATION OF NEW JERSEY.

DYE-BECK.

1,232,653.

Specification of Letters Patent. Patented July 10, 1917.

Application filed July 20, 1916. Serial No. 110,347.

To all whom it may concern:

Be it known that I, CAY BUHL, a subject of the King of Denmark, residing at Paterson, in the county of Passaic and State of New Jersey, have invented certain new and useful Improvements in Dye-Becks, of which the following is a specification.

This invention relates to dyeing machines of the class known as "dye-becks", in which the fabric or fabrics to be treated are caused to travel lengthwise through a vat containing the dyeing or other liquid by means of a rotary member or members around which the fabric extends and by which it is advanced due to frictional contact therewith, the fabric or fabrics usually having their ends temporarily secured together so as to make of each an endless band or belt that in the treatment repeatedly passes through the liquid in the vat.

In these machines means are usually provided for imparting to the part of each fabric which extends downwardly from the said advancing means (usually placed above the liquid) upon delivery therefrom a back and forth movement so as to arrange the fabric in a series of back and forth folds, thus to produce an orderly pile of the fabric and avoid thereby its bunching or becoming snarled or entangled in the liquid. The present invention consists in certain improvements in the means for imparting such movements to the fabric, the same having for their principal objects to make the mechanism more compact and simple and insure a more regular and even disposition of the folds of the fabric pile.

In the accompanying drawings,

Figure 1 is a side elevation of a dye-beck having my improvements; and,

Fig. 2 is a left hand elevation thereof.

On a suitable supporting structure including the vat *a* for the dyeing or other liquid and a frame *b* upstanding therefrom are journaled on horizontal axes the rotary drum *c* and beam *d*, connected by a sprocket-and-chain means *e* whereby rotary motion applied to the beam is transmitted to the drum.

The power for rotating the beam is derived from the motor *f*, suitably supported on the frame *b*, through a sprocket-and-chain connection *g* and a clutch-device which includes the clutch-member *h*, rotatable on the shaft *d'*, of the beam and constituting

one element of the sprocket-and-chain connection *g*, and the clutch-member *i*, splined on said shaft. The latter clutch member is adapted to be shifted outwardly to "open" the clutch and cut the beam off from the power by automatic means including the "rake" *g'* pivoted in the frame *b* and connected by the flexible device *j*, (extending around the pulley *k*) with the lever *l* engaged with clutch-member *i* in a well-known manner. The manner of operation of this means will be explained hereinafter.

The fabrics to be treated, each having its ends secured together by stitching or otherwise so as to give it the form of a belt, extend around the drum and beam as shown in Fig. 1, and they are adapted to be arranged in successive folds to form even and regular piles at the left-hand end of the vat as they are advanced through the liquid due to frictional contact with the drum and beam (rotating in the direction of the arrows in Fig. 1) by the following novel means:

A horizontal shaft *m* is journaled in the frame *b* above the vat, carrying at its ends T-heads *n* in which are arranged the arms *o*, the major portion of the length of which extends downwardly. The said arms may carry above the shaft *m* the weights *p*, adjustable thereon. At its lower end each arm is equipped with a bracket *q*, the two brackets affording journals for rollers *r* (having their axes parallel and horizontal) between which the fabrics extend on their way downwardly to enter the liquid after passing the drum. Drum *c* and shaft *m* are respectively equipped with sprocket-wheels *s* and *t* around which extends the endless chain *u*. Said shaft and the rollers *r* are respectively equipped with sprocket-wheels *v*, *w* and *x* around which and an idler sprocket wheel *x'* journaled in one of the brackets *q* extends the endless chain *y*, the disposition of which with reference to the sprocket-wheels *w* and *x* is such that both stretches thereof are on the same side of the latter, whereby advance of the chain causes the rollers to turn in opposite directions. The chain *y* being caused to rotate in the direction of the arrow in Fig. 1, the rollers of course rotate in a direction corresponding to the downward advance of the fabric.

The structure comprising shaft *m*, T-heads *n* and arms *o* and the parts carried thereby

is oscillated by a link or links z connecting the same with an eccentric portion of the drum, as shown in Fig. 1.

As the fabrics are advanced by the drum 5 and beam in the manner already stated the aforesaid structure is simultaneously oscillated. This causes the fabrics to be formed into back and forth folds in the manner shown in Fig. 1, at A, but at the bottom of 10 the vat, producing piles from the bottoms of which resumption of advance of the fabrics occurs. The rollers r are positively rotated, by the means described, in the directions of the adjoining arrows shown in Fig. 15 1, thus to prevent the part of the fabric above them, more or less heavy with the liquor, from flapping over one or the other roller and so possibly discontinuing to advance. The sprocket t is sufficiently smaller 20 than sprocket s so that the surface speed of the rollers r is greater than that of the fabric, thus to insure further the desired result of uninterrupted downward delivery.

The machine is started by shifting the 25 lever l to the position shown in Fig. 2, where the clutch is "closed." This makes taut the connection j between the lever and the "rake." The machine is manually stopped by shifting the lever reversely. Or stopping will be accomplished automatically, 30 should a bunch or tangle of the fabrics engage the arms g of the "rake," by pressure thereof against the rake, which will then be shifted in a direction corresponding to the 35 progress of the fabrics and so, through connection j , shift the lever.

The pile A is such as is formed, on the 40 removable platform of boards B, when the fabrics are to be removed from the machine, preparatory to which the stitching securing the ends of each fabric is cut so that the whole of each fabric may be ar-

ranged in a pile as the final step in the operation.

Having thus fully described my invention, 45 what I claim as new and desire to secure by Letters Patent is:—

1. In an apparatus for treating fabric, the combination of a supporting means, rotary means to advance the fabric journaled in 50 the supporting means on a horizontal axis, a swinging fabric-guiding structure pivoted in the supporting means on a horizontal axis, and a link connecting said structure with an eccentric part of the rotary advancing means.

2. In an apparatus for treating fabrics, the combination of a supporting means, rotary means to advance the fabric journaled in the supporting means on a horizontal axis, a swinging fabric guiding structure pivoted in the supporting means on a horizontal axis above the rotary means and having its fabric guiding portion below said 60 rotary means, and a link connecting said structure with an eccentric part of the rotary means.

3. In an apparatus for treating fabrics, the combination of a supporting means, rotary means to advance the fabric journaled 70 in the supporting means on a horizontal axis, a swinging fabric guiding structure pivoted in the supporting means on a horizontal axis above the rotary means and having its fabric guiding portion below said 75 rotary means and consisting of a pair of co-acting fabric guiding rollers, a link connecting said structure with an eccentric part of the rotary means, and means to transmit rotary motion from said rotary means to the 80 rollers.

In testimony whereof I affix my signature.

CAY BUHL.

Copies of this patent may be obtained for five cents each, by addressing the "Commissioner of Patents, Washington, D. C."
